BY

Thaddeus Donnelly
ATTORNEY.

UNITED STATES PATENT OFFICE

HILARY G. KNOTH, OF DETROIT, MICHIGAN

CLOTHES PROP

Application filed February 7, 1927. Serial No. 166,321.

My invention relates to a new and useful improvement in a clothes prop, and has for its object the provision of a clothes prop having telescoping parts so arranged that the prop may be adjusted to various lengths, and easily and quickly clamped in its various positions of adjustment.

Another object of the invention is the provision in a clothes prop of this class of an abutment member for limiting inward movement of one of said tubes relatively to the other, and retaining the tubes when in fully telescoped position in such a position that a pinching of the operator's hands may be prevented.

Another object of the invention is the provision of a clothes prop of this class which may be economic of manufacture and durable and highly efficient in use.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view of the invention with a part broken away.

Fig. 2 is a central vertical sectional view of the invention with a part broken away and a part shown in side elevation.

Fig. 3 is a sectional view taken on line 3—3 of Fig. 1.

Fig. 4 is a view taken on line 4—4 of Fig. 1.

Fig. 5 is a view taken on line 5—5 of Fig. 1.

The invention comprises an outer tube 7 which is reduced in diameter at its upper end 8 and provided with the axially extending split 9. Telescoping with the tube 8 is a tube 10 which is of such diameter as to form a fairly snug fit in the reduced portion 8 of the outer tube. The inner end of the tube 10 is provided with a flared abutment portion 11 which, engaging the reduced portion 8, limits outward movement of the tube 10 relatively to the tube 7. Mounted on the upper end of the tube 10 is a yoke 12 which serves to engage a clothes line or other object. Pressed into the lower end of the

tube 8 is a pointed base 13 having the sleeve portion 14 engaging in the tube 8. When these tubes are fully telescoped, the base 11 of the inner tube 10 will engage the edge of the sleeve 14, and thus limit the inward movement of the tube 10. It will be noted from the drawings that the yoke 12 is positioned considerably above the upper end of the tube 7 when these tubes are fully telescoped, this yoke 12 being provided with a bead 15. This arrangement is had so that, should the operator have the hand on the upper edge of the reduced portion 8 of the outer tube and release the inner tube 10, permitting it to move inwardly of the tube 8 by gravity, a pinching or injuring of the hand will be obviated on account of the engagement of the base 11 with the sleeve 14. To provide a clamping means so that the reduced portion 8 may be clamped against the inner tube 10 and thus retain the tubes in various positions of relative adjustment, I have provided a strap of metal 16 which embraces the reduced portion 8, and has its ends 17 and 18 turned outwardly and spaced apart. The strap 16 is preferably spot welded to the reduced portion 8, but may be secured thereto in any desirable manner.

The upper and lower edges of the end 17 are turned angularly outwardly to provide ears 19 and 20, and similarly, the upper and lower edges of the end 18 are turned angularly outwardly to provide ears 21 and 22. Projected through these ends is a threaded rod 23 upon which is fixedly mounted a circular collar 24, this circular collar being engaged by the ears 21 and 22, these ears therefore serving as a guide when the rod 23 is rotated by the angularly turned handle forming portion 25. A nut 26 is threaded on the end of the rod 23, this nut also being engaged by the ears 20 and 19, these ears therefore serving to prevent a rotation of the nut, so that when the rod 23 is turned by means of the handle 25, a threading of the rod 23 on the nut 26 will be effected. By threading the nut 26 on to the rod 23, the outwardly turned ends 17 and 18 approach each other, thus springing the split end of the portion 8 inwardly so as to securely clamp the tube 10.

I have found from experience that the use of such a clamping method is most effective, and that a very slight movement of the rod 23, when the nut 26 is held stationary, will effect the desired clamping or release of the tube 10, so that the operator, and particularly when the device is operated by a woman, will have very little difficulty in effecting the desired adjustments and clamping the tubes in their various positions of adjustment. By 10 having the ears 22 and 21 in engagement with the collar 24 a binding of the rod 23 is prevented, as these ears serve, when co-operating with the collar 24, to afford a bearing or guide, so that the ends 17 and 18 will remain in 15 alignment with each other at all times, and the nut 26 be easily and quickly threaded on or off.

While I have illustrated and described the 20 preferred form of my invention I do not wish to limit myself to the precise details of structure shown, but desire to avail myself of such variations and modifications as may come within the scope of the appended claim.

Having thus described my invention what I 25 claim as new and desire to secure by Letters Patent is:

An adjustable clothes prop of the class described comprising a pair of telescoping 30 tubes, the inner tube having on its lower end an enlargement; a line engaging member mounted on the upper end of said inner tube and provided with a portion projecting outwardly beyond the periphery of said inner tube; an engagement member mounted inwardly of the outer tube adjacent the lower end thereof, said enlarged portion on said lower end of said inner tube engaging said engagement member upon telescoping of said tubes and retaining said outwardly projecting portion of said line engaging member in 35 spaced relation to the upper end of said outer tube said inner tube upon said engagement, extending inwardly of said outer tube substantially throughout its entire length.

40 In testimony whereof I have signed the foregoing specification.

HILARY G. KNOTH.
